The ornamental design for a decorative pair of bottoms for pants, as shown and described.

DESCRIPTION

FIG. 1 is a front elevational view of a decorative pair of bottoms for pants of the present invention.

FIG. 2 is a rear elevational view thereof;

FIG. 3 is a right side elevational view thereof;

FIG. 4 is a left side elevational view thereof;

FIG. 5 is an enlarged partial front elevational view thereof;

FIG. 6 is an enlarged side elevational view thereof;

FIG. 7 is an enlarged partial rear elevational view thereof; and,

FIG. 8 is an enlarged partial view of the inside of the right leg of the decorative pant bottom of FIG. 1.

The broken lines showing the balance of a pair of pants are for the purpose of illustrating environmental matter and form no part of the claimed design.
